UNITED STATES PATENT OFFICE.

ROY S. FISHER, OF PHILADELPHIA, PENNSYLVANIA, ASSIGNOR TO TIMMONS RADIO PRODUCTS CORPORATION, OF PHILADELPHIA, PENNSYLVANIA, A CORPORATION OF PENNSYLVANIA.

ELECTRON-TUBE AMPLIFYING APPARATUS.

Application filed July 6, 1925. Serial No. 41,635.

My invention relates broadly to electron tube amplifying apparatus and more particularly to an electron tube amplifying system which has a common energy supply circuit 5 for delivering power to the cathode, anode and grid circuits of the amplifying system. Still another object of my invention is to provide an electron tube amplifier circuit employing a plurality of electron tubes in

10 which the cathode heating circuits and the anode circuits of the tubes may be supplied with energy from the usual house lighting circuit without the employment of batteries.

Another object of my invention is to provide a circuit arrangement in an electron tube amplifying system by which the power circuits of the electron tubes may be supplied with energy from the usual alternating current house lighting circuit with substantially 20 complete elimination of the hum of the alternating current in the amplifying apparatus.

Another object of my invention is to provide an arrangement of an electron tube amplifying circuit by which the proper biasing potential may be derived for the grid circuits of the several tubes, a proper value of anode potential impressed upon the anodes of the several tubes and an accurate value of 25 cathode heating current delivered to the several tubes of the series with means disposed in the amplifying circuit for substantially eliminating any trace of alternating current hum in the amplifying circuit when the circuits are supplied from the usual source of 30 house lighting current.

Still another object of my invention is to provide a circuit arrangement for electron tubes in rectifying and amplifying systems 40 in which the filament heating current of the several tubes and the plate voltage for the several tubes may be supplied from a resistance net work in which rectified alternating current is flowing.

45 A further object of my invention is to provide an electron tube system for an amplification circuit in which the output circuits of the several tubes, and the biasing potential for the grid circuits of the tubes are supplied from a series circuit in which is disposed a resistance net work for proportioning the 50 proper energy supply for the different parts of the circuit.

A still further object of my invention is to

provide a circuit arrangement for a push-pull system of amplification which may be operated in combination with the electron tube circuits of an amplifier for reproduction of the signaling energy at relatively large amplitude without interference from 60 hum normally present in the alternating current power supply from which the apparatus may be operated.

Still another object of my invention is to provide an electron tube rectifying and amplifying system having a series circuit arrangement supplied from a single source of energy of any suitable characteristic for heating the cathodes, polarizing the anodes and biasing the grids.

A further object of my invention is to provide a rectifying and amplifying system constituted by a plurality of electron tubes with a series circuit for delivering power to the circuits of a number of the tubes while power may be independently supplied to the circuits of others of said tubes which may normally require larger power than is supplied to the first mentioned tubes.

I have selected for illustration of my invention the adoption of the amplifying system to a radio receiving apparatus, although it will be understood that the amplifying system described herein is generally applicable to the detection and amplification of 85 feeble electrical currents regardless of the function for which the system is utilized.

My invention will be more fully understood by reference to the following specification, and the accompanying drawings, in which:

Figure 1 illustrates an amplification circuit arrangement employing the principles of my invention as applied to a radio receiving system; Fig. 2 is a fragmentary portion of the amplifying circuit showing one of the methods by which the cathode heating energy is supplied from the rectification circuit and the filaments of the several tubes protected against destruction; Fig. 3 illustrates the principle of my invention in connection with a plurality of electron tubes in an amplification circuit where different values of plate potential are supplied from taps taken from the resistance net work; Fig. 4 shows a modified form of amplifier circuit wherein separate resistance net works are provided for obtaining the high potential.

- supply for the detector and amplifier tubes of the receiving circuit and wherein the plate current of the last amplifier tube may be balanced against the filament currents of the preceding tubes; and Fig. 5 shows a method which I have devised for supplying power to the filament and plate circuits of electron tubes of a rectifying and amplifying system in combination with a push-pull 5 amplifier connected in the output circuit of the rectifying and amplifying system for securing reproduction of the signaling energy at large amplitude without interference from the hum of the alternating current.
- 10 Heretofore in the art sensitive electron tube amplification apparatus when operated from a source of alternating current has required that the electron tube circuits necessarily function below the point of maximum 15 sensitivity in order that the normal hum of the alternating current will not offer undue interference with the received signals. By obtaining the convenience of operation of the amplifying circuits from a standard 20 source of alternating current, it has been necessary to sacrifice sensitivity of the tube 25 circuits and accordingly when the amplifying system is utilized in a radio receiving apparatus the range of the receiving set 30 as compared to that obtainable in a battery supplied receiving set is usually considerably reduced. There are many problems in designing a radio receiving circuit which 35 may be efficiently operated from the usual source of alternating current house lighting system and it will be apparent that the periodic changes in the direction of current flow may introduce a constant source of interference in the sensitive electron tube 40 circuits unless special provision is made for eliminating the hum. Proposals heretofore made in the art for operating electron tube apparatus from the alternating current house lighting system have generally 45 utilized a circuit arrangement following the well-known principles of battery operated sets where the alternating current is introduced into the set at points normally occupied by batteries with the cathodes parallel 50 connected. I have found that this is not a desirable arrangement and that in order to overcome undesirable interference it is necessary to rearrange and modify the circuits 55 of the amplifying system as is shown in the accompanying drawings.
- I provide a current supply system for connection to the alternating current power supply, consisting of a transformer having a primary winding and secondary windings 60 arranged in different ratios for developing a relatively high potential which is rectified by a unilateral tube circuit for delivery to a resistance net work. One of the secondary windings may be arranged to supply cathode 65 heating energy to the rectifier, while still another secondary winding may be arranged for supplying alternating current direct to the cathode of the final tube of the system. The direct current network is so arranged that plate voltages of various potentials may 70 be obtained from a single source of direct current. The filament heating current also may be obtained from the same single source of direct current. The resistance network from which the plate supply is obtained is 75 connected in series with the filament circuit of several of the tubes and therefore the amount of current drawn from the direct current source is a minimum which is very 80 desirable when rectified alternating current is used, or even when a generator is employed, as the filter system can be made much smaller in size than it would normally be if operated upon larger current by reason of the low current value existent in the 85 anode circuit of the rectifier tube. The life of the rectifier tube may be considerably prolonged. While I have illustrated a single wave rectifier I desire that it be understood 90 that full wave rectification may be employed without departing from my invention. Where a tube is used in the amplifier which will have greater power capacity than the preceding tubes requiring far greater plate 95 current than the other tubes, its "plate to filament" circuit is placed in series with the filaments of the preceding tubes. This is a very economical method, so far as current consumption is concerned, and it is desirable 100 in that it allows a relatively small filter system to be used in the hum eliminating arrangement. Only single wave rectification is necessary for the elimination of hum in the amplifier of my invention, or a single 105 source of direct current with the current values at a minimum may be used by reason of the particular circuit within the amplifier. The filament of the tube in the last stage would usually require a much heavier 110 current than the preceding stages and therefore can be supplied from a separate source.
- In some arrangements of electron tubes in an amplifying circuit the "filament to plate" 115 circuit may draw less current than is required for the filaments of the preceding tubes. In this event a resistance is connected in shunt with the filament and plate of the last tube with the value of the resistances so selected that the proper current flows in the plate circuit of the last tube. This resistance 120 may also be suitably tapped to enable different potentials to be derived therefrom to furnish the plate currents of the preceding stages. In applying the principles of my invention to a radio receiving apparatus the entire control of the power supply to the several circuits may be effected by means of a rheostat in the filament circuit of the rectifier tube system. A suitable filter is employed in connection with the rectifier sys- 125

tem for blocking the alternating current from the grids of the several tubes. The biasing potential for the grids of the several tubes is obtained from taps taken from the grid returns of the radio frequency amplifier tubes and the audio frequency amplifier tubes to points in the filament circuit more negative than the cathode of the particular tube of the series. I may also provide an independent resistance and capacity network in the amplifying circuit for supplying plate voltage independently to the detector and amplifier tubes. This arrangement operates to further eliminate any AC hum from the rectifying and amplifying circuits.

Referring to the drawings in more detail reference character 1 designates an antenna system at a radio receiver connected to ground 2 and including a suitable coupling system 3 in circuit therewith tuned by condenser 4. The receiving circuit may comprise two stages of radio frequency amplification constituted by tubes 5 and 6, a detector 7 and an audio frequency amplification circuit constituted by tubes 8 and 9. The output circuit of tube 5 is interlinked with the input circuit of tube 6 through a coupling transformer 10. The input circuit of tube 6 is tuned by means of condenser 11. The output circuit of tube 6 is coupled to the input circuit of the detector tube 7 through coupling transformer 12. The input circuit of the detector tube 7 is tuned by means of variable condenser 14. The detector circuit of tube 7 includes the grid condenser and grid leak 15. The circuits of the audio frequency amplifier constituted by tubes 8 and 9 are coupled by means of audio frequency transformers 16 and 17, each of the electron tubes including a cathode or filament 5^a, 6^a, 7^a, 8^a and 9^a. The cathodes 5^a, 6^a, 7^a and 8^a are connected in series across which is shunted the protective resistance 18 which is disposed in series with a resistance network constituted by resistance units 19 and 20 with condensers 21 and 22 shunted thereacross as shown. The resistance and capacity net work is supplied with energy through the series filament circuits from the rectification circuit constituted by tube 23. The power supply apparatus includes a power transformer 24 having primary winding 25 which is connected to the usual alternating current house lighting circuit. The transformer 23 has a plurality of secondary windings 26, 27 and 28. The winding 27 is arranged to supply cathode heating energy to the rectifier tube 23 under control of the rheostat 29. The high potential supply to the rectifier 23 is derived from the winding 28 which connects to the filter circuit constituted by condensers 30 and 31 and choke coils 32 and 33. The reason for providing separate secondary windings for sup-

plying the filament circuits of the rectifier tube 23 and the filament circuit of the final amplifier tube 9 is that the winding for the cathode of the final amplifier tube must have the lowest potential above ground as possible in order to prevent the grid circuit from being modulated by the low frequency line current, the cathode winding for the rectifier tube being at a high potential above ground. The positive terminal of the direct current supply is designated at 34, while the negative terminal of the direct current supply circuit is designated at 35. In order to secure a proper value of plate voltage for the detector tube 7 a resistance unit 36 is connected between the terminal 34 and the output circuit of the tube 7. A condenser 37 is shunted across the output circuit of the detector tube 7 for by-passing the radio frequency current component. The high potential supply for the output circuit of the tubes 5, 6 and 8 is obtained by a tap taken from connection 38 in the resistance and capacity net work.

A resistance 39 is provided connected between a point in the series cathode circuit and a midpoint in a bridging resistance 40 across the cathode 9^a for establishing a negative bias on the grid of the last tube. A number of tubes of the series may have their cathodes energized by rectified alternating current, while the cathode 9^a of the final stage of amplification is represented as being supplied from the secondary winding 26 through the leads 41, by alternating current. The plate of tube 9 has the full output voltage of the rectifier tube 23 impressed upon it less the drop due to the series filament circuit of tubes 5, 6, 7 and 8. The output circuit of the tube 9 is represented at 42 and may connect to any desired form of responsive device or may lead through further stages of amplification.

The several tubes indicated at 5, 6, 7 and 8 which have their cathodes 5^a, 6^a, 7^a and 8^a in series, may be protected by connecting a resistance 18 across the series cathode circuit as indicated in Figs. 1 and 2. This resistance protects the filaments of the tubes in the event that the load is changed by removing one of the tubes. When a tube is removed a sudden rush of current occurs on account of the condensers discharging which may cause some of the other tubes to burn out. The resistance 18 placed across the cathodes of the radio frequency amplifier tubes, the detector and the first tube of the audio amplifier operates to absorb fluctuations in energy and protects the cathodes. I have also illustrated in Fig. 4 the last tube 9 of the series as having a high resistance 44 and a shunting capacity 43 arranged in the input circuit serving as a filter to block any 60 cycle AC variation from the grid and to protect the input transformer against any 130

accidental heavy rush of current or excessive current in the grid circuit of this tube. Such instantaneous rise of current resulting for example, by the shorting of the grid 5 and plate electrodes might permanently destroy the operating efficiency of the amplifier. In order to secure the desired negative potential for biasing the grids of the radio frequency amplifier tubes 5 and 6 and the 10 audio frequency amplifying tube 8 connections are taken from taps in the filament circuit to the grids of the tubes at points which are more negative than the cathodes of each of the tubes. That is to say, the control 15 electrode in tube 5 is connected to a point 51 in the series cathode circuit which point is more negative than the cathode 5^a. The control electrode of tube 6 is connected to a point 52 in the series cathode circuit which 20 point is more negative than the cathode 6^a. The control electrode for tube 8 is connected to a point 53 in the series cathode circuit which is more negative than the potential 25 of the cathode 8^a. By selecting a proper point in the series cathode circuit an exact operating potential may be obtained.

In Fig. 3 of the drawings, I have illustrated the arrangement where the single 30 source of direct current across the terminals 34 and 35 energizes the cathodes 5^a, 6^a, 7^a, 8^a and 9^a connected in series with the resistance capacity net work comprising resistances 19, 20 and 49 connected in series with the cathode circuit. Condensers 21, 22 and 35 50 are connected in shunt with each of the sections or portions of the resistance net work 19, 20 and 49. Taps are taken at points 38, 49 and 55 for obtaining the desired anode operating potential for the receiving system.

In Fig. 4, I have shown a complete radio 40 receiving system embodying the principle of my invention where the entire control is effected by means of rheostat 29 in the cathode circuit of rectifier tube 23. The final stage 45 of audio frequency amplification is shown having its cathode 9^a heated from a source of alternating current delivered from secondary winding 26 as distinguished from the direct current operation of the cathodes 5^a, 6^a, 7^a and 8^a of the tubes 5, 6, 7 and 8 respectively. The input circuit of the tube 9 is provided with filter paths 43 and 44 for blocking the alternating current from the grid. I have shown a high frequency choke 50 coil 56 in the rectifier circuit and a fuse 57 also disposed in the rectifier circuit for protecting the rectifier in the event that a condenser or portion of the apparatus becomes short circuited.

In Fig. 5 of the drawings I have illustrated the application of my invention to a 60 push-pull amplification system connected to the audio frequency circuit of the amplifier. The push-pull amplifier tubes are represented by reference characters 58 and 59 having

cathodes 58^a and 59^a respectively. The input circuit for the push-pull amplifier is illustrated as including a transformer 60 having secondary windings 61 and 62 connected in the respective tube circuits. The output energy from the push-pull amplifier is delivered through a transformer 63 having primary windings 64 and 65 and a secondary winding 66. A single source of direct current supply is provided between terminals 70 34 and 35 serving to impress direct current on the cathodes of tubes 5, 6, 7 and 8 in a circuit which includes the plates of the push-pull amplifier consisting of tubes 58 and 59 and the plates of tubes 5, 6, 7 and 8. With 75 this combination the plate current of the push-pull amplifier tubes 58 and 59 is maintained equal to the filament current of tubes 5, 6, 7 and 8. The tubes 5, 6, 7 and 8 have 80 cathodes, 5^a, 6^a, 7^a and 8^a, which normally require low filament current. The tubes 58 and 59, which are normally of considerably 85 larger power capacity type than the radio and audio frequency amplification and detector tubes, each require a plate current of approximately half the current required by tubes 5, 6, 7 and 8. The combination of 90 the two plate circuits operating together equals the filament current of tubes 5, 6, 7 and 8 and therefore can be connected in series with these tubes. The cathodes 58^a and 59^a may be operated from a source of 95 alternating current derived from winding 26 as heretofore described. The common input circuit for the push-pull amplifier is connected between a mid-point on the shunting resistance 40, regulating resistance 39, and hum-eliminating circuit 44 and 43 with a 100 mid-point between secondary windings 61 and 62. The operation of the amplifying circuit is maintained free from hum of the 105 alternating current supply. The protective resistance 18 is connected across the series cathode circuit for preventing sudden rush of current by reason of condenser discharge or variation in load. This resistance protects the filaments of the tubes in case one of the tubes is removed from its socket. I have found that if a tube is removed it causes a sudden rush of current on account 110 of the condenser discharging, which has often caused some of the other tubes to burn out. The resistance 18 absorbs any rush of energy and thereby protects the tubes.

My invention has been found to be very 115 efficient in practical operation and while I have illustrated the principles of my invention embodied in various forms, I desire that it be understood that modifications may be made and that no limitations upon the invention are intended other than those imposed by the scope of the appended claims.

What I claim and desire to secure by Letters Patent of the United States is as follows:

1. An amplification system comprising in combination a plurality of electron tubes each having a cathode, an anode and a control electrode, an input circuit for each of said tubes including said cathode and control electrode, an output circuit for each of said tubes including said anode and cathode, means interlinking the output circuit of each of said tubes with the input circuit of a succeeding tube, circuit connections to a source of alternating current, means for rectifying said current, a resistance net-work, connections including a filter system between said resistance net-work and said rectifying means, a pair of electron tubes having divided input circuits coupled with the output circuit of the last electron tube of the series, a series circuit including the cathodes of said first mentioned electron tubes and a portion of said resistance network in shunt with the space discharge path of said pair of electron tubes, connections for heating the cathodes of said pair of electron tubes from alternating current, and means connected in series with the control electrodes of said pair of electron tubes for eliminating the hum of alternating current in said receiving system.
2. An amplification system comprising in combination a plurality of electron tubes each having a cathode, an anode and a control electrode, an input circuit for each of said tubes including said cathode and control electrode, an output circuit for each of said tubes including said anode and cathode, means interlinking the output circuit of each of said tubes with the input circuit of a succeeding tube, a source of alternating current, means for rectifying said current, a resistance net-work, connections including a filter system between said resistance net-work and said rectifying means, a pair of electron tubes having divided input circuits coupled with the output circuit of the last tube of the series, a series circuit including the cathodes of said first mentioned electron tubes and a portion of said resistance network in shunt with the space discharge path of said pair of electron tubes, means for independently energizing the cathodes of said pair of electron tubes, and connections between said resistance network and the anodes of said first mentioned electron tubes for deriving differing potentials for the anodes of said first mentioned electron tubes.
3. An amplification system comprising in combination a plurality of electron tubes with the output circuit of one tube inter-linked with the input circuit of a succeeding tube, each of said tubes having grid, filament and plate electrodes and at least one of said tubes having larger power capacity than others of said tubes, a resistance network, connected across the output circuit of one of said last mentioned tubes, a series circuit including the filament electrodes of a number of said tubes, said series circuit being connected in series with a portion of said resistance network whereby the current supply to said filament electrodes and the output circuit of said tube of larger power capacity is governed by said resistance network.
4. An amplification system comprising in combination a plurality of electron tubes with the output circuit of one tube inter-linked with the input circuit of a succeeding tube, each of said tubes having grid, filament and plate electrodes and at least one of said tubes having larger power capacity than the others of said tubes, a resistance network, a series circuit containing the filament electrodes of the tubes of less power capacity than said first mentioned tube, and a circuit including the plate electrode of said larger power capacity tube connected in series with a portion of said resistance network, said resistance net-work being shunted across the plate circuit of said larger capacity tube.
5. An amplification system comprising in combination a plurality of electron tubes with the output circuit of one tube inter-linked with the input circuit of a succeeding tube, a pair of electron tubes having their input circuits coupled with the output circuit of said first mentioned tubes, each of said tubes having grid, filament and plate electrodes said pair of electron tubes having larger power capacity than said first mentioned tubes, an impedance network, and a series circuit including the filaments of said first mentioned tubes in series with a parallel connection between a portion of said impedance network and the plate electrodes of said larger power capacity tubes.
6. An amplification system comprising in combination a plurality of electron tubes with the output circuit of one tube inter-linked with the input circuit of a succeeding tube, each of said tubes having grid, filament and plate electrodes and at least one of said tubes having larger power capacity than the others of said tubes, a series circuit containing the filament electrodes of the tubes of less power capacity than said last mentioned tube, said series circuit including the plate electrode of one of said tubes of larger power capacity and a resistance network having a portion thereof connected in shunt with the series circuit including the filament electrodes of the tubes of less power capacity than said last mentioned tube.
7. An amplification system comprising in combination a plurality of electron tubes with the output circuit of one tube inter-linked with the input circuit of a succeeding tube, a pair of electron tubes having larger power capacity than said first men-

tioned electron tubes, each of said tubes having grid, filament and plate electrodes, said pair of electron tubes having a larger power capacity than said first mentioned electron tubes, with the plate electrodes thereof connected in parallel, with respect to the plate current supply, a resistance network, a series

circuit including the filament electrodes of said first mentioned electron tubes and a portion of said resistance network, and connections between said resistance network and the plate circuits of said pair of larger power capacity electron tubes. ¹⁰

ROY S. FISHER.
